IMPELLER AGITATOR

Application filed March 25, 1929. Serial No. 349,732.

This invention relates to agitators of the circulation type, in which a rotating impeller in the tank produces a vertical current with a return flow in the opposite direction. The 5 invention particularly relates to agitators of this type employing a draft tube surrounding the impeller for directing the fluid circulation.

When employed in continuous operation, 10 that is, with a continuous feed and discharge, agitators of this type are designed with relation to the flow so that the liquid to be agitated will have a predetermined detention period adequate to produce the necessary 15 mixing, dissolution, reaction or other operation. However, it has been found that individual portions of the feed may not be retained in such agitators for the predetermined detention period, as some portions of 20 the feed may tend to short-circuit across the agitator to discharge, while other portions are detained an abnormal length of time in 25 the agitator. This condition is decidedly objectionable, particularly where complete chemical reaction between constituents is necessary.

The primary object of this invention is, therefore, to provide a circulation agitator, in which direct short-circuit from the feed 30 inlet to the discharge outlet will be positively prevented and detention for less than the desired period will be minimized, this arrangement in turn resulting naturally in a corresponding elimination of excessive detention. This object is, in general, attained by 35 connecting the draft tube with the tank walls as by baffles or partitions arranged so as to direct all of the feed to the inlet end of the draft tube without permitting any of the 40 feed to pass the sides of the tube.

The secondary object of the invention is to provide a draft tube arrangement which is simple and practical for large installations constructed of concrete, in which the support 45 of the draft tube is a substantial problem. This object, likewise, is solved by the use of the partitions above mentioned, which serve as convenient and strong supporting means for the draft tube. Where an upward central current is employed, a transverse parti-

tion beneath the draft tube may be installed, which positively prevents particles descending on the feed side from shooting across the bottom and rising on the outlet side of the draft tube which would tend to reduce their 55 detention period; but this arrangement is distinctly alternative and optional, since ordinarily such particles would in any event be sucked up in the rising current. Likewise, a transverse partition above the draft tube 60 may be employed, with the same result as where the partition is installed beneath the tube, the partition beneath the tube being retained, if desirable, so that there would be a partition entirely surrounding the tube. 65

It is to be understood that the apparatus is not necessarily limited to an upward flow in the draft tube, since it will likewise operate with a downward flow on substantially the same principle. Furthermore, it is not 70 limited to the use of a mechanical impeller or propeller, as shown, since other lifting arrangements, such as compressed air or other gas, are known and in general use.

Other objects and advantages of the invention will be apparent from the following description taken in connection with the accompanying drawings, in which

Fig. 1 is a vertical sectional view of an embodiment of my invention; 80

Fig. 2 is a plan; and

Fig. 3 is an enlarged detail view, partly in section, showing the manner of attachment of the impeller to the shaft, and also the foot bearing and its connection with the shaft and 85 the supporting beam.

Referring to the drawings, 1 designates a tank made of reinforced concrete or other suitable material and having at opposite sides thereof a feed inlet or launder 11 and a discharge outlet or launder 12 at substantially the normal liquid level in the tank. The tank is here shown as square, but it should be understood that the tank may be circular or of any other suitable conformation. Positioned centrally in the tank and between the feed inlet and the discharge outlet is a draft tube 13 with its upper end below the normal liquid level and its lower end spaced above the bottom of the tank. 95 100

Within the draft tube there is a rotary number 14 in the form of an impeller which is mounted on a vertical shaft 15 suspended from a platform 16 carried by cross members 17 in the form of I-beams and supported on opposite sides of the tank. The shaft is driven through a speed reducer 18 by a motor 19, both of which are mounted on the platform 16; and at its lower end is guided or maintained in alignment by a foot bearing 20 including a bushing 21 serving to receive the shaft and being adjustable for centering the shaft by means of threaded bolts or screws 22 mounted horizontally in a flange projecting upwardly from a plate 23 secured by bolts 24 to a cross bar or beam 25 extending across the draft tube intermediate its ends and secured thereto. The hub of the impeller is mounted on the shaft loosely enough to permit sliding and rests on a projection 26 on the shaft, said projection being preferably in the form of a pin; and relative rotation between the shaft and the impeller is prevented by suitable means such as a key or feather 27 entering suitable grooves in the shaft and impeller, the key 27 being tapered or of wedge shape so as to hold such members tightly together.

The structure thus far described may be substantially of usual form. In operation the feed enters continuously at the inlet 11 and an equivalent amount of treated fluid or liquid is displaced and overflows through the discharge outlet 12, but in passing through the tank the liquid is subjected to the action of the impeller 14 which, as here shown, tends to produce flow of the liquid upwardly through the draft tube and downwardly at the periphery of the tank, as indicated by the arrows in Fig. 1.

As already stated, individual portions of the feed material may not be retained in the agitator for the predetermined detention period, due to a tendency to short circuiting across the tank to the discharge outlet, and this action would be accompanied by detention for an abnormal or excessive length of time of other portions of the feed. It will be apparent that the flow at the outlet end of the draft tube tends to spread in all directions and therefore to prevent short circuiting at such end; and that short circuiting is more likely to occur at the sides of the draft tube and across the inlet end of the tube, although probably less likely at the inlet end of the tube than at the sides.

According to the illustrated embodiment of the invention, the agitator is provided with vertical partitions 30 extending from the shaft tube 13 to the side walls of the tank 1, and substantially in a vertical plane passing through the axis of the draft tube and perpendicular to the vertical plane through the axis of the inlet and the outlet. This arrangement serves to prevent any portion of

the feed from passing around the draft tube at the sides thereof. These partitions may also extend to the bottom of the tank and upwardly above the normal liquid level.

There may also be a transverse partition 31 extending across the lower or inlet end of the draft tube and serving positively to prevent material descending at the feed side of the tank from shooting across the bottom thereof and rising on the outlet side of the draft tube, thus tending to reduce the detention period of such material. This arrangement is, however, optional and may or may not be used, inasmuch as such material would ordinarily, instead of shooting past the lower end of the draft tube, be carried up into the tube by the current passing upwardly therethrough. It might be desirable to provide a similar transverse partition at the upper end of the draft tube, especially if the current through the draft tube is downward. In either case, it would be desirable to have the partition extend from the level of the innermost point of the inlet end of the tube to the corresponding surface of the fluid at the top or bottom of the column of material in the tank.

Another important feature of the invention resides in the utilization of the partitions 30, the partition 31, or both of them to support the draft tube which may be of reinforced concrete, and is of considerable weight. To this end, the partitions 30 are connected directly with the draft tube and are supported by the side walls, floor or both; and the draft tube rests on the partition 31. In order to support the draft tube 13 at points outside the plane of the partitions 30 and 31, there may be provided posts 32 interposed between the lower edge of the draft tube and the floor of the tank. Preferably there are two of such posts which are arranged in the vertical plane between the inlet and the outlet.

It will be apparent from the foregoing description that various modifications and changes in the arrangement shown may be made without departing from the spirit and scope of the invention. In particular it should be understood that by partition is meant any structure connecting or interposed between the draft tube and the side walls of the tank for the purposes indicated.

I claim:

1. In an agitator, the combination with a tank having an inlet and an outlet spaced from each other, a relatively large open ended draft tube communicating at its lower end with the lower part of said tank and extending upwardly therefrom, and means for producing a current through said draft tube, of means extending across the inlet end of the tube in the tank and extending to the bottom of the tank and completely across the same for preventing the passage of liquid

- from the inlet to the outlet across the inlet end of the tube, said means having supporting engagement with the draft tube.
2. In an agitator, the combination with a tank having an inlet and an outlet spaced from each other, of a relatively large open ended draft tube, means extending from the draft tube to the wall of the tank at two different positions and extending substantially throughout the height of the tank to prevent passage of material in either direction around the tube from said inlet to said outlet, said means having supporting engagement with the draft tube and means for producing a current through said draft tube.
3. In an agitator, the combination with a tank having an inlet and an outlet spaced from each other, a draft tube in said tank communicating at its lower end with the lower part of said tank and extending upwardly, and means for producing a current through said draft tube, of a partition at each side of the tank between the inlet and the outlet and extending from the draft tube to the tank and serving to support the draft tube from the tank.
4. In an agitator, the combination with a tank having an inlet and outlet spaced from each other, a relatively large open ended draft tube inside the tank communicating at its lower end with the lower part of the tank and extending upwardly therefrom, and means for producing a current through said draft tube, of a partition on each side of the tank between the inlet and the outlet and extending from the draft tube to the side wall of the tank and serving to support the draft tube in the tank.
5. In an agitator, the combination with a tank having an inlet and outlet spaced from each other, a relatively large open ended draft tube in said tank communicating at its lower end with the lower part of said tank and extending upwardly therefrom, and means for producing a current through said draft tube, of a partition at each side of the tank between the inlet and the outlet, extending from the draft tube to the bottom of the tank and serving to support the draft tube in the tank.
6. In an agitator, the combination with a tank having an inlet and outlet spaced from each other, a relatively large open ended draft tube communicating at its lower end with the lower part of said tank and extending upwardly therefrom and having its upper end below the solution level in the tank and means for producing a current through said draft tube of a partition at each side of the tank between the inlet and the outlet and extending from the draft tube to the wall of the tank upwardly above the solution level in the tank for preventing the passage of liquid from the inlet to the outlet around said tube, said means having a supporting engagement with the draft tube.
7. In an agitator, the combination with a tank having an inlet and outlet spaced from each other, a relatively large open ended draft tube open at both ends communicating at its lower end with the lower part of said tank and having its upper open end below the solution level in the tank, and means for producing a current through said draft tube, of means extending across the inlet end of the tube in the tank between the inlet and the outlet for preventing passage of liquid from the inlet to the outlet across the inlet end of the tube, and means extending from the draft tube to the wall of the tank throughout the entire height of the same for preventing passage of liquid from the inlet to the outlet around the draft tube, said means having supporting engagement with the draft tube in the tank.
8. In an agitator, the combination with a tank having an inlet and outlet spaced from each other, a relatively large open ended draft tube communicating at its lower end with the lower part of said tank and extending upwardly therefrom and means for producing a current through the tube, of partitions on each side of the draft tube between said inlet and said outlet, said partitions resting on the bottom of the tank and serving to support the draft tube in the tank, and additional means extending between the bottom of the tank and the draft tube for supporting the same.
- In testimony whereof I affix my signature.
- ARTHUR W. BULL.
